(57) **CLAIM**

The ornamental design for a glue extruder device, as shown and described.

DESCRIPTION

FIG. 1 is a perspective view of the glue extruder device showing my new design;
FIG. 2 is a front side view thereof;
FIG. 3 is a rear side view thereof;
FIG. 4 is a right side view thereof;
FIG. 5 is a left side view thereof;
FIG. 6 is a top view thereof; and,
FIG. 7 is a bottom view thereof.

1 Claim, 6 Drawing Sheets

FIG. 1

FIG. 2

FIG. 3

FIG. 4

FIG. 5

FIG. 6

FIG. 7
